CLAIM

The ornamental design for a butter or condiment dispenser, as shown and described.

DESCRIPTION

FIG. 1 is a top, front, left side perspective view of a butter or condiment dispenser showing my new design;

FIG. 2 is a left side elevational view thereof;

FIG. 3 is a rear elevational view thereof;

FIG. 4 is a front elevational view thereof; and

FIG. 5 is a rear elevational view thereof.

The undisclosed bottom view is plain and unornamented.

FIG. 1

FIG. 3

FIG. 2

FIG. 5

FIG. 4
